UNITED STATES PATENT OFFICE.

ROBERT B. ROBISON, OF CADDO, TEXAS.

WIRE-LINE SPOOLER.

1,348,448.

Specification of Letters Patent. Patented Aug. 3, 1920.

Application filed March 28, 1919. Serial No. 285,800.

To all whom it may concern:

Be it known that I, ROBERT B. ROBISON, a citizen of the United States, residing at Caddo, in the county of Stephens and State 5 of Texas, have invented certain new and useful Improvements in Wire-Line Spoolers; and I do hereby declare the following to be a full, clear, and exact description of the invention, such as will enable others 10 skilled in the art to which it appertains to make and use the same.

This invention relates to spoolers, and more particularly to a spooler specially adapted for winding or spooling a wire line 15 or cable such as is commonly used in connection with oil well boring operations.

One of the main objects of the invention is to provide a spooling mechanism by means of which the wire line may be readily 20 wound onto a spool, the spool and associated parts being then locked tightly against reverse movement, and the loose end of the line being secured, so as to effectually prevent 25 unwinding of the line.

25 A further object is to provide a spooler including a connecting and winding block which is connected to a winding shaft so as to be capable of independent vertical adjustment, which secures uniformity in spool- 30 ing.

35 A further object is to provide simple and efficient means whereby, when the spooling operation is complete, the connecting and winding block may be locked to the winding shaft so as to prevent relative movement between these two members.

Further objects will appear from the detailed description.

In the drawings:

40 Figure 1 is a side view of a spooler constructed in accordance with my invention in set up position, as used.

Fig. 2 is a section taken substantially on line 2—2 of Fig. 1.

45 Fig. 3 is an inside plan view of one section of the connecting and winding block.

Fig. 4 is a central longitudinal section through the connecting and winding block and associated parts.

50 Fig. 5 is a detail front view of the connecting head of the winding shaft.

Fig. 6 is a side view of the spooler with the crank block removed showing the wide

spool and all parts of the spooler in locked position. 55

Fig. 7 is a section taken on line 7—7 of Fig. 6.

The winding shaft designated generally by 1 is adapted to be rotated from the main drive wheel of a rig such as is commonly employed in oil well drilling operations. This winding shaft comprises an inner section 2 and an outer section 3 the inner end of which is threaded and is screwed into a corresponding socket or recess formed in the outer end of section 2. The inner end portion of inner section 2 of the shaft is of circular cross section and is threaded to receive a locking nut 4 screwed thereon, this nut being positioned adjacent the inner end 70 of a bearing sleeve 5 which fits snugly upon the intermediate squared portion 2^a of section 2. This sleeve is provided with a central outer annular shoulder or rib 6 of substantial V-shape in cross section which fits 75 into a corresponding groove formed in the head 7 of a supporting jack designated generally by 8, and in the cap plate 9 which is bolted on the upper face of head 7 and cooperates therewith to rotatably support and 80 secure the bearing sleeve. The jack may be of any suitable or preferred construction and is utilized to rotatably support the sleeve and the parts associated therewith. This jack is braced by suitable rods 9^a and 85 turnbuckles 9^b interposed therein, the rods being secured at their upper ends to cap 9 and, at their lower ends, to the walk A of the drilling outfit. In this manner, the winding shaft and associated parts are 90 rotatably supported and, when desired, by removing the cap plate 9, these members may be removed from the jack and placed in any suitable position.

An inner clamping plate 10 is mounted on 95 the intermediate squared portion 2^a of inner section 2 of the shaft, this plate being provided with a central aperture corresponding approximately to the cross section of the squared portion 2^a, the plate being slidable 100 on the shaft while secured against independent rotation thereon. This plate 10 is adapted to coöperate with a similar plate 11 which fits tightly upon an enlarged annular shoulder 12 provided at the outer end 105 of squared portion 2^a, outward movement of

this plate 11 being positively limited by an annular shoulder 13 formed at the outer end of shoulder 12, to clamp a spool 2^b mounted upon the shaft between plates 10 5 and 11.

Outer section 3 of the spooling or winding shaft is provided, at its outer end, with a substantially spherical head 14 which fits loosely into a corresponding socket 15 formed 10 in the inner member 16^a of block 16. This member 16^a is of substantial rectangular cross section and is composed of two sections 17 and 18 which are detachably secured together by screwbolts 19, or in any other 15 suitable manner. This inner end portion of block 16 is provided with a rectangular recess 20 which snugly receives the body portion 21 of a centering block 22 having a peripheral flange 23 provided with spaced 20 openings which receive machine screws 24 by means of which this block may be secured to the inner end of the connecting and spooling block. As will be noted more 25 clearly from Figs. 2 and 5, section 3 fits loosely through an enlarged substantially frusto-conical opening 25 provided through the centering block 22, and the head 14 is provided with four diametrically opposite radially projecting pins 26 which fit into 30 grooves 27 communicating directly with the socket 15 and extending longitudinally thereof. These grooves receive the pins so as to produce a loose connection whereby an appreciable amount of looseness or play is 35 permitted between the head 14 and the block 16. This permits the spooling shaft, and the spool carried thereby to be adjusted vertically by means of the jack during rotation of the shaft so as to secure uniform 40 spooling of the line.

Inner member 16^a of block 16 is further provided, at its outer end, with a central reduced neck 28 which fits snugly into a corresponding bore extending axially of outer 45 block member 16^b. This bore communicates with a recess 29 extending from one side of member 16^b, this recess permitting ready access to a securing nut 29 screwed upon the reduced end 30 of neck 28 and co-operating therewith to hold the blocks tightly together. A lock pin 31 is inserted through block member 16^b and engages into a recess 28^a provided in neck 28 for this purpose, this pin being normally locked in position by a 50 set screw 32. In this manner the block members are secured together for simultaneous rotation, and by withdrawing the locking pin 31 the inner member 16^a and the spooling shaft and the parts associated therewith 55 may be rotated independently of member 16^b for unspooling the wire in a manner to be later described.

The outer end portion of block member 16^b is reduced and tapered to provide an 60 outwardly tapering substantially frusto-

conical stem 33 which is threaded, this stem being adapted to be screwed into a corresponding socket or opening 34 provided adjacent the lower end of a crank block 35. This crank block is provided adjacent its 70 outer end with an opening 36 for receiving the upper end of a brace rod 37 in which is interposed a turnbuckle 38, the lower end of this rod being secured through a similar opening 39 provided through the upper end 75 of plate 11, for rigidly connecting block 16 and the spooling shaft when lowering the spooler. A pin 40 is secured through block 35 beyond the opening 34 and is provided, on its inner end, with a thickened head 41. A 80 pin 42 is secured through the block inside of pin 40 and is provided with a head 43 of less thickness than the head of pin 40. These pins provide means for detachably securing block 35 to a crank arm 44 secured on one end 85 of the main drive shaft of the rig, this shaft being rotated from the engine in the well known manner.

A centering head 45 of frusto-conical shape is loosely mounted on the outer section 3 of the spooling shaft for movement toward and away from the centering block. This head is secured in adjustment by a set screw 46 and when moved into its outermost position engages snugly into the opening or socket 25 of this block so as to secure the same, and the block 16, in properly centered position relative to outer section 3 of the spooling shaft.

In practice, the winding shaft 1 is connected, by means of block 35 and pins 40 and 42, to the drive shaft of the rig so as to be rotated thereby when the engine is driven in normal or operating direction, the spool being disposed at right angles to the plane 100 of the line to be spooled, as in Fig. 1. The cable or wire to be spooled, which is wound upon the shaft of bull wheel 47, is led upwardly beneath the water table of the tower B, passed over the crown pulley C, and then 105 downwardly to the spool, the free end of the line being then secured to the spool upon which it is to be wrapped or wound. When the spooling shaft is rotated, the line is drawn from the bull wheel shaft and wound 110 upon the spool. When the line has been completely wound upon the spool, the free end of the line is secured thereto and the centering head is forced into the opening 25 of the centering block 22 so as to center 115 block 16 relative to shaft section 3. In this connection, it is to be noted that the head 14 at the outer end of this shaft section is of greater diameter than the inner end of the opening 25 so as not to be drawn therethrough during the centering operation. The block 16 may thus be readily secured in 120 centered relation to the shaft section 3 and all looseness or play between this shaft section and the block prevented. The various 125 130

members of the spooler are thus readily secured against all relative looseness or play, and the free end of the line is effectually secured so as to eliminate all possibility of 5 unwinding thereof. When the wire has thus been secured, pin 42 is removed and block 35 turned downwardly about pin 40, crank arm 44 being turned downwardly and the spooler being then lowered by means of 10 the jack so as to be supported upon the walk A by this block and the jack. The pins 40 and 42 of this crank block may also be utilized in lowering the free end of the spooler so as to prevent injury or distortion thereof. 15 In the event that it becomes necessary to replace the bull wheel shaft before the drilling is completed, the line is spooled in the manner above described, the bull wheel shaft replaced, and the line is then wound from the 20 spool back onto the shaft. For this purpose, block member 16^a is disconnected from member 16^b by withdrawing the locking pin, thus permitting free rotation of the spool and the spooling shaft in the manner previously described.

It will be evident that there may be slight changes made in the construction and arrangement of the details of my invention without departing from the field and scope 30 of the same, and I intend to include all such variations, as fall within the scope of the appended claims, in this application in which a preferred form only of my invention is disclosed.

35 What I claim is:

1. In spooling means, a rotatable shaft, a spool carried thereby, a connecting block comprising an inner member and an outer member, universal connections between said 40 inner member and said shaft, means for securing said block members together adapted to permit independent rotation of the inner member, means for normally locking said inner member to the outer block mem-

ber, and means carried by the outer block 45 member for securing the same to the drive shaft of a well rig for rotation therewith.

2. In spooling means, a rotatable shaft provided at its outer end with a substantially cylindrical head having diametrically 50 opposite radially projecting ears, a connecting block provided with a socket loosely receiving the head of the outer section of said shaft and having diametrically opposite 55 grooves loosely receiving the ears of said head, a centering block secured in the inner end of said connecting block and provided with an opening of greater diameter than the outer section of the shaft so as to permit vertical adjustment of the shaft, and means 60 for centering said block relative to the shaft and for securing the shaft and block against relative movement.

3. In spooling means, a rotatable spool shaft, connecting blocks, a universal joint 65 structure connecting said blocks with one end of said shaft, and a crank block secured to the outer end of said connecting block and adapted to be secured to a crank arm of the drive shaft of a well rig for rotating 70 said spool shaft when the rig is operated.

4. A spooling device including a rotatable shaft, a connecting block, a universal joint structure connecting said block with one end of said shaft, a centering block secured to 75 said connecting block about the shaft and provided with an opening of greater diameter than the shaft so as to permit vertical adjustment of the shaft, and means for centering said block relative to the shaft and 80 for securing the shaft and block against relative movement.

In testimony whereof I affix my signature in presence of two witnesses.

ROBERT B. ROBISON.
